United States Patent Office

Des. 212,996
Patented Dec. 17, 1968

212,996

COIN DISPLAY CASE

Carlos Sierra-Franco, King of Prussia, Pa., assignor to
The Franklin Mint, Inc., a corporation of Pennsylvania

Filed Nov. 30, 1967, Ser. No. 9,588

Term of patent 14 years

(Cl. D87—3)

FIG. 1

FIG. 2

FIG. 3

FIG. 4

I claim:

The ornamental design for a coin display case, substantially as shown and described.
